UNITED STATES PATENT OFFICE.

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LUBRICATOR FOR LOOM PICKER SPINDLES.

Application filed February 7, 1928. Serial No. 252,616.

This invention relates to a lubricator for loom picker spindles and it is the general object of the invention to provide a device of this kind which is controlled by some part 5 of the picking mechanism so that there will be no chance for the element which has direct contact with the picker spindle to be in the path of the picker when the latter is in shuttle propelling position.

10 In practically all drop box looms and on the plain ends of many automatic weft replenishing looms the picker mechanism includes a rod or a spindle substantially parallel to the lay and along which a rawhide 15 picker is caused to slide by a picker stick. A portion of the picker is slotted to receive the picker stick while another portion engages the tip of the shuttle. As the picker moves back and forth along the spindle it is 20 found that the latter becomes heated, especially in fast running looms. There ordinarily is no way of distributing a small amount of oil over the surface of the spindle such as is desirable to prevent spattering of 25 oil on the yarn or cloth as the picker moves inwardly and it is an object of my present invention to deposit a very thin film of lubricant together with resilient means which tend normally to move the lubricating element 30 away from the spindle.

It is a more particular object of my present invention to employ a lubricating element of paraffin, wax or some similar substance which is normally solid and melts at 35 a comparatively low temperature. Such a lubricant will lubricate the spindle only at such times as the latter is sufficiently hot to melt a small amount of the lubricant.

With these and other objects in view 40 which will appear as the description proceeds, my invention resides in the combination and arrangement of parts hereinafter described and set forth in the claims.

In the accompanying drawings, wherein 45 I have shown a convenient embodiment of my invention,

Fig. 1 is a fragmentary top plan view of one end of a loom showing the shuttle box in rearmost position with the picker stick 50 actuating the lubricating device,

Fig. 2 is a rear elevation taken in the direction of arrow 2, Fig. 1,

Fig. 3 is a view similar to Fig. 1 with the picker stick and picker moved inwardly

so that the lubricating device is not actuated, 55 and

Fig. 4 is a fragmentary view taken on line 4—4 of Fig. 2, showing a method of holding the lubricant.

In a loom which has a single shuttle box 60 at one end it is customary to have the picking mechanisms at the ends of the loom actuated on alternate beats. By this arrangement the picker stick is actuated at the end 65 of the loom where the active shuttle happens to be located. The picker stick and parts moving therewith start to propel the shuttle across the loom when the lay is going backwardly and has reached its mid position, or 70 at a point which is termed in the trade "top center." When the lay reaches "back center" the picker stick will ordinarily be in an inward position on the picking side of the 75 loom and will not return to its outer position until the lay has started on its forward movement. My present invention makes use of this fact and enables me to support the movable parts of the device on a fixed pivot.

Referring more particularly to Figs. 1 and 80 2 I have shown a loom frame 10 and a lay L provided with a shuttle box B which receives the shuttle S. The shuttle box has projecting from the rear side thereof two spaced lugs 11 and 12 which afford support 85 for a picking spindle 13. The inner end of the spindle, the right hand end as viewed in the drawings, is received by a small bushing 14 which is of conical form, as indicated in Fig. 1, and is seated in the inner lug 11. The outer end of the spindle passes through 90 a bore 15 formed in the lug 12 and is held in position by a screw 16 threaded into said lug 12. The method of support for the picker spindle forms no part of my present invention and may if desired be similar to 95 that shown in patent to Lanciault No. 1,594,620.

The picker stick is indicated at 17 and 100 may be actuated by any picking mechanism not shown to have an inward movement or a movement from the full line position to that shown in dotted lines in Fig. 2 on every alternate beat of the loom when there is a single box at one end of the lay L. A 105 picker 18 is provided with a bearing 19 through which extends the spindle 13 and said picker also has a shuttle engaging portion 20. That portion of the picker be-

tween the bearing 19 and the shuttle engaging part is provided with a slot 21 through which extends the upper end of the picker stick 17. The picker extends through the 5 wall 22 forming the rear part of the box B and is adapted to slide along and be guided by the picker spindle. The matter thus far described is of common construction and forms no part of my present invention, being the usual form of picking arrangement found on drop box looms and on certain weft replenishing looms.

In carrying my invention into effect I provide means for periodically depositing a 15 small amount of lubricant on the spindle 13. A stand 30 which is secured by means of a bolt 31 to the loom frame 10 is provided with an upstanding stud 32 which extends through a slot 32^a and may be held in 20 an adjusted position in said slot by a nut 33 on the lower end thereof. The upper portion of the stud has mounted thereon two relatively movable levers 34 and 35 having hubs 36 and 37, respectively, through which the 25 stud extends. A coiled spring 38 surrounds portions of the hubs 36 and 37 and has one end extended behind the lever 35 as at 39 while the other end is extended behind the lever 34 as at 40. The lever 35 has a projecting finger 41 which is held against an upstanding pin 42 carried by the lever 34 by means of the spring 38. By this construction the two levers 34 and 35 may move 30 around the stud without relative movement but when occasion requires said levers may move independently of each other because 35 of the yielding action permitted by the spring 38. A light tension spring 43 interposed between the pin 42 and a second pin 44 on the stand tends to hold the lever 34 against a stop 45 carried by the bracket 30 so that the parts are normally in the position 40 shown in Fig. 3.

The left hand end of the actuating lever 35 45 is designed for cooperation with the picker stick and has a head 46 formed substantially as shown in Fig. 3, said head being covered, if desired, with a coating of leather or other suitable material 47 which will operate to reduce shock, wear and noise. The head is provided with an inclined surface 48 adapted for cooperation with the picker stick 17 should the latter move to the left 50 while the head 46 is in its path.

The right hand end of the lubricant supporting lever 34 may be as shown in Fig. 4, said end being formed with a pocket 49 which receives the lubricating element 50 which in the present instance may be a block 55 of paraffin, wax or other solid lubricant which melts at a relatively low temperature. For certain features of my invention, however I am not limited to the particular form of lubricant, as the levers already described will operate satisfactorily independ-

ently of the type of lubricant or lubricating element employed. As shown in Figs. 2 and 4 the pocket 49 lies in substantially the same horizontal plane as the spindle 13 so that the lubricating element 50 may have 70 substantial contact with said spindle.

Under normal operation the picker stick will be in the position shown in Fig. 2 in full lines on one pick, namely, when the shuttle is being picked toward the plain end 75 of the loom, and will be in the position indicated in dotted lines in Fig. 2 on the next pick when the lay is in the rear position indicated in Figs. 1 and 3. When the picker stick is in the position shown in Fig. 2 it 80 will engage the head 46 as the lay nears the rearward part of its stroke to rock the actuating lever 35 and the lubricant carrying lever 34 around stud 32. During this movement a time will come when the lubricating 85 element 50 will engage the spindle 13, after which continued rear movement of the actuator lever 35 will result in stressing the spring 38 and in moving the finger 41 away from the stop pin 42. By means of the 90 yielding of said spring it is unnecessary to have the lever accurately timed or located with respect to the motion or position of the lay. The yielding of said lever 35 also permits the lubricant to be in contact with the 95 spindle an appreciable length of time. It will be understood that when the levers are rocked as described the picker will be to the left as shown in Fig. 2 where it cannot interfere with the operation of the lubricating 100 device.

When the picker stick has been moved to the dotted line position in Fig. 2 to propel the shuttle to the opposite side of the loom, said stick will not engage the actuator lever 105 35 and the latter will be held in the position shown in Fig. 3 by the light tension spring 43. When in this position the lubricating element 50 is out of the path of the picker so that the latter is free to move to the position shown in Fig. 3 without interference 110 on the part of the lubricant 50. The time when the picker stick starts to move toward the outer end of the shuttle box depends somewhat upon the setting of the picking 115 cam not shown and should the picker stick move to the left early in the pick of the loom it will engage the inclined portion 48 and move the lever 35 in a counter-clockwise direction around the stud 32. This 120 movement of the two levers will take place after the picker has been moved away from the range of movement of the lubricant 50.

While I have shown the invention in connection with a loom having a plain or single 125 shuttle box at one end yet I do not wish to be limited to this construction as certain features of the invention may operate satisfactorily even though a single box be not present in the loom.

From the foregoing it will be seen that I have provided a simple lubricating device actuated by the picker stick and constructed to yield so that the lubricant may remain in contact with the picker spindle an appreciable length of time and also be spared the sudden shock, noise and wear on the picker stick which would result if the actuating and lubricating carrying elements were formed in one piece. It will further be seen that when the device is used in the particular embodiment set forth herein it can operate only on alternate beats of the loom and that this operation is dependent upon the picker stick. It will further be seen that I have provided the loom with a picker spindle lubricant which is normally solid but which melts at a sufficiently low temperature to operate successfully because of the heat generated on the picker spindle by the movement of the picker. It will also be seen that because of the fact that the device is dependent for its operation on the picker stick it is impossible for the lubricating element to get in the path of the picker or be damaged by contact with the latter.

Having thus described my invention it will be apparent that changes and modifications may be made therein by those skilled in the art without departing from the spirit and scope of the invention and I do not wish to be limited to the details herein disclosed, but what I claim is:

1. In a lubricating device for an elongated member carried by the lay of the loom, means movable substantially parallel to the member to propel the shuttle, and a lubricating device operated by the shuttle propelling means to be moved into lubricating engagement with the elongated member.

2. In a picker spindle lubricating device for a loom having a lay, a picker stick and a picker movable thereby along the spindle, a lubricating member normally spaced from the spindle, and means actuated by the picker stick as the lay moves to move said lubricating member into engagement with the spindle.

3. In a picker spindle lubricating device for a loom having a lay, a picker stick and a picker movable thereby along the spindle, a pair of resiliently connected elements movable about a fixed axis, one of said elements to be engaged by the picker stick as the lay moves backwardly to cause the other element to move toward the spindle, and a lubricating member carried by said other element to have contact with the spindle.

4. In a picker spindle lubricating device for a loom having a lay, a picker stick and a picker movable thereby along the spindle, a two part rocking device, one part of which is adapted for actuation by the picker as the lay moves and the other part of which is movable toward the spindle when the first

part is actuated by the picker stick, yielding means to hold said parts in normal position, and a lubricating member carried by one of the parts to have engagement with the spindle when the other part is engaged by the picker stick.

5. In a picker spindle lubricating device for a loom having a lay, a picker stick and a picker movable thereby along the spindle, a pivoted device having a portion to be engaged by the picker stick as the lay moves, a lubricating member carried by another part of said device adapted for engagement with the spindle, and a member interposed between the picker stick and the lubricator member to yield when the picker stick engages said device.

6. In a picker spindle lubricating device for a loom having a lay, a picker stick and a picker movable thereby along the spindle, a lubricating member, and means establishing a yielding connection between the picker stick and said member and operative by the picker stick as the lay moves to move the lubricating member into engagement with the picker stick.

7. In a picker spindle lubricating device for a loom having a lay, a picker stick and a picker movable thereby along the spindle, a pair of levers, means to hold said levers yieldingly in a given position, one of said levers to engage the picker stick as the lay moves, and a lubricating member carried by the other lever and movable into engagement with the spindle when the first named lever engages the picker stick.

8. In a picker spindle lubricating device for a loom having a lay, a picker stick and a picker movable thereby along the spindle, a pair of levers, a common pivotal support for said levers, yielding means to hold said levers in a given position, and a lubricating member carried by one of said levers and movable into engagement with the spindle when the other of said levers is engaged by the picker stick as the lay moves.

9. In a picker spindle lubricating device for a loom having a lay, a picker stick and a picker movable thereby along the spindle, a movable device having a portion normally lying in the path of the picker stick as the lay moves, and a lubricating member carried by said device and positioned for engagement with the picker spindle, said device to be engaged by the picker stick on those beats of the loom when the picker stick is at rest relatively to the lay to move said lubricating member into engagement with the spindle.

10. In a picker spindle lubricating device for a loom having a lay, a picker stick and a picker movable thereby along the spindle, the picker stick to be active during certain beats of the loom and inactive during certain other beats of the loom, and a lubricating de-

vice for the picker spindle rendered operative by the picker stick on those beats of the loom when said picker stick is in its inactive position.

- 5 11. In a picker spindle lubricating device for a loom having a lay, a picker stick and a picker movable thereby along the spindle, a substantially solid lubricating member having a relatively low melting temperature, and means rendered operative by the picker stick as the lay moves rearwardly to move said lubricating member into contact with the picker spindle, the heat of the picker spindle melting a small amount of the lubricant which is left on the spindle.
- 10

12. In a picker spindle lubricating device for a loom having a lay, a picker stick and a picker movable thereby along the spindle, a substantially solid lubricant having a relatively low melting temperature, a yielding support for said member, and an actuator for said support to be engaged by the picker stick as the lay moves, said actuating member tending to move the support more than is necessary to cause engagement between the picker spindle and the lubricant when the latter is of maximum size.

In testimony whereof I have hereunto affixed my signature.

RICHARD G. TURNER.
